UNITED STATES PATENT OFFICE.

JAMES WILLIAM HARRIS AND STEPHEN HARRIS, OF SALTILLO, MISS., ASSIGNS OF ONE-HALF TO J. A. BALLARD & SON, OF SAME PLACE.

PLOW.

SPECIFICATION forming part of Letters Patent No. 290,641, dated December 18, 1883.

Application filed October 2, 1883. (No model.)

To all whom it may concern:

Be it known that we, J. W. HARRIS and STEPHEN HARRIS, of Saltillo, in the county of Lee and State of Mississippi, have invented 5 certain new and useful Improvements in Plows; and we do hereby declare the following to be a full, clear, and exact description of the invention, such as will enable others skilled in the art to which it pertains to make 10 and use it, reference being had to the accompanying drawings, which form part of this specification.

Our invention relates to an improvement in plows; and it consists in the combination of 15 two beams, one of which is placed upon the other, and the colter, which is passed down through both of the beams, the lower beam being made slotted, so that it can be adjusted back and forth in relation to the colter, and 20 thus bring the edge of the colter nearer to or farther from the shovel, as will be more fully described hereinafter.

The object of our invention is to provide a 25 means by which the colter and the shovel can be adjusted in relation to each other, according to the kind of work which is being done.

Figure 1 is a side elevation of our invention. Fig. 2 is an inverted view, the rear end of the 30 lower beam being cut away so as to show the rear slot.

A represents an ordinary wooden beam, to the rear end of which the handles B are secured in the usual manner.

Clamped to the under side of the beam A 35 by means of the bolts C is a second metallic

beam, D, which is provided with slots for the bolts C and the colter F to pass through.

Upon the top of the beam A is placed a suitable metallic plate, I, so as to prevent the nuts upon the tops of the bolts C from injuring the wood, and to prevent the key J, which is used to tighten the colter in place, from unnecessarily enlarging the opening through which the colter is passed. By means of the slots O in the ends of the metallic beam, this 40 beam can be adjusted back and forth on the under side of the beam A, and thus bring the point of the shovel nearer to or farther from the colter, as may be desired. 45

When the metallic beam is moved forward, 50 the shovel is made to approach nearer to the colter, and there is not so much room then left for weeds, cornstalks, and other such trash to catch upon the bent portion of the standard and clog the plow.

Having thus described our invention, we 55 claim—

In a plow, the combination of the wooden beam, the slotted metallic beam, which is applied to its under side, and which is adjustable back and forth upon the clamping-bolts C, and the colter, which passes down through 60 both of the beams, substantially as described.

In testimony whereof we affix our signatures in presence of two witnesses.

JAMES WILLIAM HARRIS.
STEPHEN HARRIS.
